Specification for Design.

Patented Sept. 12, 1905.

Application filed August 3, 1905. Serial No. 272,613. Term of patent 7 years.

To all whom it may concern:

Be it known that I, FREDERICK HABENSACK, a citizen of the United States, and a resident of Sag Harbor, in the county of Suffolk and State of New York, have invented a certain new, original, and ornamental Design for the Handle of a Spoon, Fork, or Similar Article, of which the following is a specification.

In the accompanying drawings, Figure 1 is a view of the obverse side, and Fig. 2 of the

reverse side, of the handle of a spoon or fork having my design applied thereto.

What I claim is—

The ornamental design for the handle of a spoon, fork or similar article, as shown.

FREDERICK HABENSACK.
